HIS ATTORNEY

UNITED STATES PATENT OFFICE.

EDWARD H. BUCKLEY, OF PHILADELPHIA, PENNSYLVANIA.

SKYROCKET.

Application filed March 10, 1925. Serial No. 14,370.

To all whom it may concern:

Be it known that I, EDWARD H. BUCKLEY, a citizen of the United States, residing at Philadelphia, in the county of Philadelphia and State of Pennsylvania, have invented certain new and useful Improvements in Skyrockets, of which the following is a specification.

My invention relates to sky-rockets and more particularly to the sky-rocket stick.

There is danger of falling sky-rocket sticks injuring persons or objects they strike. Numerous attempts have been made to overcome this objection, but have failed for various reasons. Some sticks were either too costly or unreliable in functioning, others were both costly and unreliable.

The objects of my invention are to provide a sky-rocket stick which is inexpensive, which will avoid the above danger by separating into small and light pieces which float down or fall lightly through the air, and which is reliable in its function.

These objects, and other advantageous ends which will be described hereinafter, I attain in the following manner, reference being had to the accompanying drawing in which—

Figure 1 is a side elevation of a sky-rocket having my stick attached thereto illustrating it partly broken away, and

Figure 2 a picture view illustrating how my stick is made.

Referring to the drawing, 1 indicates a sky-rocket and 2 the stick secured to the sky-rocket by wire clamps 3. The stick consists of a readily separable tube 4 filled or partly filled with light granular material 5. It is made by spirally winding a strip 6 as shown in Figure 2. Its lower end is closed by twisting the strip as shown at 7. After the tube is charged, its upper end is closed by twisting the free end 8 of the strip as shown at 9. The free end of the strip and the upper end of the tube are fastened to the sky-rocket by the wire clamps 3 and the free end is thus prevented from unwinding until the rocket explodes.

The greater part of the granular material 5 may be confetti, saw dust or other material which will float or fall lightly through the air, but in case any light material is

used, there should be sufficient sand or other heavy material to provide the proper balance. The strip 6 may be of paper, cloth or other sheet material.

When the sky-rocket is ignited and forced upward through the air, the stick will guide it to travel in substantially one direction. When the rocket explodes the free end of the strip will be released from between the sky-rocket body and the wire clamps. It will then unwind and allow the granular material to fall and scatter. The strip and granular material will float and fall lightly through the air and will not injure persons or objects upon which they may fall.

If the strip and granular material are otherwise inflammable, they should be impregnated with a fire-proof compound.

While I have described my invention as taking a particular form, it will be understood that the various parts may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. A rocket stick consisting of a separable tube of light sheet material and containing granular material.

2. A rocket stick consisting of a tube made by winding a strip of light material spirally, and containing granular material.

3. In combination with a rocket, a separable tube made by winding a strip of light material spirally; means for clamping one end of the tube and the strip to the rocket, and granular material within the tube.

4. In combination with a rocket, a separable tube having its lower end closed and consisting of a strip of light material wound spirally; means for clamping the upper end of the tube and the free end of the strip to the rocket, and granular material within the tube.

In testimony whereof I have signed my name to this specification.

EDWARD H. BUCKLEY.
